PRODUCTION AND/OR SEPARATION OF NON-IONIC SURFACE ACTIVE AGENTS

Dennis Henry Desty and Charles Leslie Arthur Harbourn, Sunbury-on-Thames, England, assignors to The British Petroleum Company Limited

No Drawing. Application December 14, 1953,
Serial No. 398,206

Claims priority, application Great Britain
December 31, 1952

10 Claims. (Cl. 260—103)

This invention relates to an improved process for the production and/or separation of non-ionic surface active agents.

It is well known that by the condensation of ethylene oxide in the presence of fatty acids, resin acid, alcohols, alkylated phenols or mercaptans, products having an ethylene oxide chain are obtained which are of considerable utility as surface active agents. The length of the ethylene oxide chain is an important factor in determining the surface active characteristics of the compound in which it is contained. Thus according to length of the ethylene oxide chain, compounds of a particular type, differing only in respect of this chain length, find primary utility as foaming agents, dispersing agents, wetting agents, emulsifying agents, solutizers or as detergents.

It is a characteristic of the condensation reaction by which these surface active agents are formed that it is not possible to obtain with ease a single compound as product of said reaction and, in general, the product obtained consists of a mixture of compounds, said compounds differing one from another in respect of the length of the ethylene oxide chain. Thus, in general, by commercially feasible processes, the surface active agent obtained, while containing compounds of pre-eminence in utility for a particular function, will contain substantial proportions of compounds having greater utility for a different function.

It is an object of the invention to provide a process for the fractionation of non-ionic surface active agents comprising mixtures of surface active compounds, to obtain fractions differing in surface active characteristics.

It is another object to provide a process for the production of non-ionic active agents, having a desired surface active characteristic, in improved yields.

According to the present invention there is provided a process which comprises adding a precipitating agent to a solution of a non-ionic surface active agent in an organic solvent, said surface active agent comprising a mixture of surface active compounds having, in the molecule, a chain of ethylene oxide groups, the surface active agent being only partially soluble in said precipitating agent and said precipitating agent being a liquid which is miscible with said solvent, whereby part of said surface active agent is thrown out of solution, and thereafter recovering the precipitated fraction.

When the non-ionic surface active agent comprises a mixture of surface active compounds having, in the molecule, ethylene oxide chains of differing length, the fraction precipitated will contain an increased proportion of compounds having relatively long ethylene oxide chains and the remaining solution will contain an increased proportion of compounds having a relatively short ethylene oxide chain.

If desired the process may be operated to give a plurality of precipitated fractions, for example by progressive additions of the precipitating liquid or by modifica-

2

tion of the reaction conditions, as by progressively decreasing the temperature.

Operating in the manner described, it is possible to obtain two or more fractions from a "mixed" non-ionic surface active agent, each of the said fractions being of particular utility as a wetting agent or as an emulsifying agent or as a detergent.

According to another aspect of the present invention there is provided a process which comprises reacting

- 10 ethylene oxide with a suitable organic compound whereby a non-ionic active agent is formed comprising a mixture of surface active compounds having, in the molecule, ethylene oxide chains of differing lengths and thereafter, in the presence of a solvent therefor, added to the reaction mixture or to the reaction product, fractionally precipitating part of the product, comprising compounds having an ethylene oxide chain of at least the desired length, by the addition of a precipitating agent comprising a liquid which is miscible with said solvent and in
20 which said agent is only partly soluble and thereafter recycling at least part of the remainder of the product, comprising compounds having a relatively short ethylene oxide chain, to the reaction mixture comprising ethylene oxide and said organic compound.
- 25 Suitable organic compounds for reaction with ethylene oxide to form surface active agents are fatty acids, resin acids, alcohols, alkylated phenols and mercaptans.

Suitable solvents for the non-ionic surface active agents are low molecular weight aliphatic alcohols and ketones, 30 preferably having 1-3 carbon atoms/molecule, for example, ethanol and acetone; aromatic hydrocarbons, for example, benzene and toluene; naphthenes, for example cyclopentane and cyclohexane and chlorinated hydrocarbons, for example, carbon tetrachloride and chloroform.

35 A preferred solvent is cyclohexane.

Suitable precipitating agents are saturated aliphatic hydrocarbons, for example, normal-pentane, iso-hexane, normal-hexane, isopentane, normal-heptane, iso-octane. A preferred material is iso-hexane.

- 40 It is also possible, by the process of the present invention, to effect a separation of mixtures of compounds containing an ethylene oxide chain, based on dissimilarities in molecular structure other than ethylene oxide chain length. Thus, for example, it is possible in accordance with the process of the invention to fractionate mixtures containing compounds in which there are differences in the structure of the group associated with the ethylene oxide chain or in the manner of attachment of said group to said chain. The operation of a process in this manner lies within the scope of the invention.
- 45

50 Fractions of non-ionic surface active agents, precipitated in the manner herein described are very suitable for use as feedstocks to a process for the formation of solid non-ionic surface active agents by reaction with urea as described in British patent application Serial No. 697,315.

The invention is illustrated but in no way limited by the following examples.

55 "Lissapol NXA" is a surface active agent having the formula

60 where R is an alkyl group having, on the average, 8 carbon atoms; A is a benzene ring; and in which the value of n varies, being approximately 12. "Lissapol" is a registered trademark.

Example 1

65 Thirty grams of "Lissapol NXA" was dissolved in 200 ml. of cyclohexane. Iso-octane was progressively added, the mixture being stirred after each addition, until approximately 10 grams of surface active agent had been

thrown out of solution. The lower layer consisting of the precipitated liquid surface active agent was removed, being referred to hereinafter as fraction 1.

The addition of iso-octane to the remaining solution was continued until a further 10 grams of surface active agent had been thrown out of solution. The lower layer consisting of the precipitated liquid surface active agent was removed, being referred to hereinafter as fraction 2.

The remaining mixture of surface active agent, cyclohexane and iso-octane was distilled to remove cyclohexane and iso-octane overhead, the residual surface active agent constituting fraction 3.

Example 2

This example illustrates the difference in properties of the feedstock, that is, untreated "Lissapol NXA" and fractions 1, 2 and 3. In each case the liquid surface active agent was converted to solid form by the process described in the specification filed in respect of British patent application Serial No. 697,315.

(a) 10 grams of "Lissapol NXA," 100 ml. of normal pentane and 1 ml. of methanol were mixed and thereafter, 20 grams of urea added. The mixture was stirred for 1 hour, allowed to stand for 48 hours and then filtered. The solid product, after evaporation of residual solvent, was a dark brown, slightly tacky powder.

(b) 10 grams of fraction 1, 100 ml. of normal pentane and 1 ml. of methanol were mixed and thereafter, 20 grams of urea added. The mixture was stirred for 30 minutes, allowed to stand for 2 hours, by which time a satisfactory product had formed and then filtered. The solid product, after evaporation of residual solvent, was a fine, light brown free-flowing powder.

(c) 10 grams of fraction 2, 100 ml. of normal pentane and 1 ml. of methanol were mixed and thereafter, 20 grams of urea added. The mixture was stirred for 30 minutes. After standing for 2 hours the adduct was not yet in a condition for filtration. After 12 hours standing a satisfactory adduct had been formed. This was filtered off and residual solvent evaporated off. The product was a fine, light brown free-flowing powder.

(b) 10 grams of fraction 3, 100 ml. of normal pentane and 1 ml. of methanol were mixed and thereafter, 20 grams of urea added. The mixture was found to be unsuitable for the formation of a solid adduct in the form of a free-flowing powder.

The above experiments clearly show that fractions 1, 2 and 3 differ in properties from the feedstock and from each other. Furthermore the precipitated fractions, fractions 1 and 2 are superior to the feedstock and to fraction 3 in the ease of formation of solid adducts with urea and in respect of colour of product.

We claim:

1. A process for the fractionation of a non-ionic surface active agent containing a mixture of surface active poly ethyl oxy condensation products of compounds selected from the group consisting of fatty acids, resin acids, alcohols, alkylated phenols and mercaptans to obtain fractions differing in surface-active characteristics, which comprises adding a saturated aliphatic hydrocarbon as a precipitating agent to a solution of said surface active agent in an organic solvent selected from the group consisting of low molecular weight alcohols, low molecular weight ketones, aromatic hydrocarbons, naphthenes and chlorinated hydrocarbons, said surface active agent being only partially soluble in said precipitating agent and said precipitating agent being a liquid which is miscible with said solvent, whereby part of said surface active agent is thrown out of solution to form a precipitated fraction and thereafter recovering said fraction.

2. A process for the production of a non-ionic surface active agent which comprises reacting ethylene oxide with an organic compound selected from the group consisting of fatty acids, resin acids, alcohols, alkylated phenols and

mercaptans to form a non-ionic surface active agent therewith containing a mixture of surface active compounds having, in the molecule, ethylene oxide chains of differing lengths and thereafter, in the presence of an organic solvent selected from the group consisting of low molecular weight alcohols, low molecular weight ketones, aromatic hydrocarbons, naphthenes and chlorinated hydrocarbons, fractionally precipitating part of the product containing compounds having an ethylene oxide chain of at least the desired length by the addition of an unsaturated aliphatic hydrocarbon as a liquid precipitating agent which is miscible with said solvent and in which said agent is only partly soluble, and thereafter recycling at least part of the remainder of the product containing compounds having a relatively short ethylene oxide chain to the reaction mixture comprising ethylene oxide and said organic compound.

3. A process for the production of a non-ionic surface active agent which comprises reacting ethylene oxide with an organic compound selected from the group consisting of fatty acids, resin acids, alcohols, alkylated phenols and mercaptans to form a non-ionic surface active agent therewith, containing a mixture of surface active compounds having, in the molecule, ethylene oxide chains of differing lengths and thereafter, in the presence of an organic solvent selected from the group consisting of low molecular weight alcohols, low molecular weight ketones, aromatic hydrocarbons, naphthenes and chlorinated hydrocarbons, fractionally precipitating part of the product containing compounds having an ethylene oxide chain of at least the desired length by the addition of an unsaturated aliphatic hydrocarbon as a liquid precipitating agent which is miscible with said solvent and in which said agent is only partly soluble, and thereafter recycling at least part of the remainder of the product containing compounds having a relatively short ethylene oxide chain to the reaction mixture comprising ethylene oxide and said organic compound.

4. A process as specified in claim 1 in which the precipitating agent is added in a plurality of stages, a precipitated fraction being recovered at each stage.

5. A process as specified in claim 1 in which the solution remaining after removal of the precipitated fraction is subjected to distillation, for the removal of organic solvent and precipitating agent, and recycling the surface active agent to the reaction mixture comprising ethylene oxide and said organic compound.

6. A process as specified in claim 1 in which the organic solvent is cyclohexane.

7. A process as specified in claim 1 in which the precipitating agent is iso-hexane.

8. A process as specified in claim 3 in which the organic solvent is cyclohexane.

9. A process as specified in claim 3 in which the precipitating agent is iso-hexane.

10. A process as defined in claim 1, in which each of the compounds forming the mixture of non-ionic surface-active compounds is a compound having the formula

wherein R is an alkyl group and A is a phenylene group, R in the mixture having an average of 8 carbon atoms and A in the mixture having an average value of 12.
